UNITED STATES PATENT OFFICE.

HERBERT W. MORREALL, OF PINE GROVE, PENNSYLVANIA.

FURNACE-DOOR FASTENER.

Application filed July 19, 1926. Serial No. 123,538.

The doors of furnaces are frequently forced open by pressure from within due to various causes. This endangers the life and limb of the attendant by reason of escaping steam, gases or water, besides materially interfering with the action of the furnace, and filling the air with noxious odors, gases and products of combustion, all of which is objectionable and overcome by the present invention which provides means for securing the door when closed.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a front view of a furnace door embodying the invention.

Figure 2 is an end view of the door and frame, with the invention applied.

Figure 3 is a detail perspective view of the parts illustrated in Figure 2, a portion of the door and frame being broken away, and illustrating the manner of releasing the door latch by means of the handle, and

Figure 4 is a detail sectional view on the line 4—4 of Figure 2.

Corresponding and like parts are referred to in the following description and designated in the several views of the drawings by like reference characters.

The numeral 1 designates the setting or body of a furnace having a door opening to which is fitted a frame 2. The door 3 is hinged to the frame 2 in any preferred way and when closed, is prevented from casual opening by the usual stop 4 and catch 5, the latter constituting a projection of the door 3 and the stop 4 forming a part of the frame 2. As shown most clearly in Figure 2, the stop 4 is beveled in opposite directions for the catch 5 to ride upon, the inner bevel being adjacent the frame 2 and coacting with the catch 5 to retain the door 3 in closed position in a manner well understood.

In accordance with the present invention, a bracket 6 is attached to the end of the door frame 2 provided with stop 4 and is substan-

tially of V-form and is provided at its outer end or apex with an eye 7 which constitutes a bearing for the journal or pivot 12 of a latch 8. The latch 8 consists of a bar which is pivoted near its outer end to the bracket 6 and which is disposed to have its inner end engage the catch 5 to prevent outward movement thereof and the casual opening of the door 3 by any pressure exerted thereagainst from within the furnace. The latch 8 inclines inwardly and downwardly, so that the inner end in contact with the catch 5 is below a horizontal line passing through the pivot of the latch and in consequence the door is fastened or securely held against opening when the latch is in operative position, as shown most clearly in Figure 2. A pin 9 projects laterally from the inner end of the latch 8 and is disposed between the members or legs of the bracket 6, and acts jointly with the spaced members of the bracket to limit the pivotal movement of the latch.

The latch 8 is disposed in the path of the catch 5 and when closing the door 3 the catch 5 rides over the stop 4 and beneath the catch 5 and when the door reaches a closed position the catch 5 engages the inner beveled portion of the stop 4 and the latch 8 clears the catch 5 and drops in front thereof and secures or fastens the door against accidental opening from pressure exerted thereagainst within the furnace. When it is required to open the door 3 the outer end of the latch 8 is depressed a distance to cause its inner end to clear the catch 5, when the door may be opened in the usual way. In many instances the door 3 is provided with a handle 10 which is pivoted to a lug formed upon the outer side of the door adjacent the catch 5. In order that the handle 10 may be utilized as means for releasing the latch 8, the latter is provided at its outer end with a laterally disposed pin 11, and when it is required to open the door 3 the swinging end of the handle 10 is elevated to a point above the pin 11 and is swung laterally to engage over said pin. Downward pressure exerted upon the handle 10 operates the latch to clear the catch 5 and a pull upon the handle opens the door in the usual way.

It will be understood that the invention is extremely simple, strong, durable, cheap, capable of being installed upon any furnace at a nominal expense, and is effective to au-

automatically secure a door when closed and easy of operation to release and open the door when required.

Having thus described the invention, I claim:

1. The combination with a furnace door provided with the usual stop and catch for retaining the same in closed position, of fastening means comprising a latch mounted upon the furnace and adapted to engage the said catch and prevent casual disengagement thereof from the stop, the pivot of the latch being in a higher plane than the catch to admit of the latch inclining inwardly and downwardly to prevent accidental disengagement from the catch.
2. The combination with a furnace door provided with the usual stop and catch for retaining the same in closed position, of a bracket disposed adjacent the swinging end of the door, and comprising spaced upper and lower portions, a latch pivoted to the bracket and adapted to incline inwardly and downwardly and engage the said catch to prevent accidental disengagement thereof from the stop, and a pin projecting laterally from the latch and disposed between the upper and lower spaced portions of the bracket and limited in its pivotal movement thereby.
3. The combination with a furnace door provided with the usual stop and catch for retaining it in closed position, a handle pivoted to the door, of a latch pivotally mounted upon the furnace and adapted to engage the said catch to prevent disengagement thereof from the stop, and having a lateral extension adapted to be engaged by the pivoted handle of the door, whereby the latch may be disengaged from the catch and the door opened by manipulation of the pivoted handle.
4. The combination with a furnace door provided with the usual stop and catch for retaining the door in closed position, of a substantially V-shaped bracket adapted to be mounted upon the furnace adjacent the stop and a latch pivoted adjacent its outer end to the said bracket and adapted to incline inwardly and downwardly and engage the catch to prevent accidental disengagement thereof from the stop.
5. The combination with a furnace door provided with the usual stop and catch for retaining the door in closed position, of a V-shaped bracket adapted to be mounted upon the furnace adjacent the stop, and having an eye at its outer end, a latch pivoted adjacent its outer end to the bracket and adapted to incline inwardly and downwardly to engage the catch and prevent accidental disengagement thereof from the stop, and a pin projecting laterally from the catch and operating between the members of the bracket.

In testimony whereof I affix my signature.
HERBERT W. MORREALL. [L.S.]
